UNITED STATES PATENT OFFICE.

LENA F. FERRELL, OF LA MONTE, MISSOURI.

DESIGN FOR A SHOE-LACE FASTENER.

SPECIFICATION forming part of Design No. 33,180, dated September 11, 1900.

Application filed July 30, 1900. Serial No. 26,353. Term of patent 14 years.

To all whom it may concern:

Be it known that I, LENA F. FERRELL, a citizen of the United States, residing at La Monte, in the county of Pettis and State of Missouri, have invented and produced a new and original Design for a Shoe-Lace Fastener, of which the following is a specification.

This invention relates to a design for a shoe-lace fastener, and the leading feature consists in the design forming the subject-matter of the accompanying illustration.

The drawing represents a perspective view of a shoe-lace fastener embodying the features of the design.

The design is characterized by the main or body portion 1, which is of diamond shape, with two transversely-alined centrally-disposed apertures 2. From the opposite ends

of the body continuous members 3 extend inwardly and merge into regularly-curved bends 4, and continuous with the latter are outwardly-extending reduced tongues 5, having a concave contour and located over the said members 3 and project beyond the emanating points of the latter.

Having thus described the invention, what is claimed as new is—

The design for a shoe-lace fastener, herein shown and described.

In testimony that I claim the foregoing as my own I have hereto affixed my signature in the presence of two witnesses.

LENA F. FERRELL.

Witnesses:

WILL W. FERRELL,
BERTHA FERRELL.
